UNITED STATES PATENT OFFICE.

FRED W. RIBLET, OF NEWAYGO, MICHIGAN.

DEVICE FOR ABSTRACTING LAND TITLES.

No. 800,397.

Specification of Letters Patent.

Patented Sept. 26, 1905.

Application filed July 21, 1904. Serial No. 217,579

To all whom it may concern:

Be it known that I, FRED W. RIBLET, a citizen of the United States, residing at Newaygo, in the county of Newaygo and State of Michigan, have invented certain new and useful Improvements in Devices for Abstracting Land Titles; and I do hereby declare the following to be a full, clear, and exact description of the invention, such as will enable others skilled in the art to which it appertains to make and use the same.

My invention relates to an improved device for abstracting land titles; and its object is to provide a more convenient, accurate, and simple means for making sets of abstracts from the public records and keeping them renewed to date and to provide a more convenient and simple means for tracing land titles, to provide means whereby the abstracts can be readily reproduced, if destroyed, and to provide a device having various new and useful features, as will hereinafter more fully appear and be particularly pointed out in the claims, reference being had to the accompanying drawings, in which—

Figure 1 is a perspective of a tray or drawer containing a quantity of cards as they appear after having been prepared for filing and filed in the tray; Fig. 2, a plan of one of the cards adapted for abstracting lands described by sections, quarters, and sixteenths of sections, town, and range as said card appears before preparation for filing; Fig. 3, the same of a card adapted for abstracting platted lands; Fig. 4, the back of a card for abstracting mortgages or other incumbrances of titles; Fig. 5, a plan of a page of a book to be used in conjunction with the cards shown in Fig. 2, and Fig. 6 the same of a book to be used in conjunction with the cards shown in Fig. 3.

Like letters refer to like parts in all of the figures.

A represents any suitable tray or drawer to contain the cards and having on the front blanks to be filled out with the number of the section, together with the town and range to which the entries on the cards in the tray relate.

B represents cards adapted to abstract titles of land described by section and divisions of section. These cards are first prepared as shown in Fig. 2. The upper edge is divided into four equal parts, representing quarter-sections, by recesses D, which form channels running through the upper edges of the cards

when the same are arranged in the tray A, and the divisions between the recesses are lettered "of N. E.," "of N. W.," "of S. W.," "of S. E." to correspond to the respective quarters of a section of land, and each division is provided with four upwardly-projecting tabs C, adapted to be detached from the cards by any suitable means, and each series of four tabs is lettered "N. E.," "N. W.," "S. W.," "S. E." to respectively indicate the respective quarters of a quarter-section or sixteenth of a section or any lesser part thereof, and on the face of the card when the same is used is written the abstract of any particular deed, mortgage, or any other instrument, as occasion requires. Blanks L are also provided on each card for entering the section, town, range, date, date of record, liber, and page of the public records relating to the instrument abstracted. Obviously if the land referred to is divided otherwise than by quarters and sixteenths the tabs of each card would be divided into a number of groups corresponding to the number of main divisions of the land and each group contains tabs equally numbered to the subdivisions of each main division or minor divisions of the land.

For abstracting platted lands the tray should be provided with a blank on the front indicating the part of a block, block or blocks, and plat to which the contained cards relate and cards, as in Fig. 3, provided, having similar recesses D, preferably four, and five tabs C', provided to each subdivision of the cards between the recesses, and these tabs numbered from "1" to "20," consecutively, thus being divided into groups of five by the recesses, whereby the number indicating any particular lot of a given block is more readily found. If the block contains less or more than twenty lots, the channels and tabs may be modified in number accordingly. On these cards are also ruled lines for the abstract and blanks M, in which are entered the block, plat, date, date of record, liber, and page of the particular instrument abstracted. For mortgages or other assignable instruments I provide cards having their backs prepared as shown in Fig. 4, said backs being provided with vertical lines dividing the same into several parts, preferably four, as shown at Q, one of which is provided with blanks in which to enter the date of the instrument, the date of record, and the liber and page of the public records, with the word "Discharged," and a blank to enter the name of

the party discharging the same, the other parts being marked "Assigned" and having blanks for the name of the assignee, date of instrument, date of record, liber, and page of record. Thus these cards when properly filled out show an abstract of the mortgage on the face of the card and all assignments and the discharge of the same, if any, on the back, and thus furnish a complete history of the instrument. I also provide a book or books having pages ruled as in Fig. 5 and having columns F for entering the date of record, columns G for the liber, and columns H for the page of the public records of each instrument abstracted under the particular head shown at the top of the page, the various headings at the tops of the pages of the book being a duplicate of the manner of labeling each tray, as shown in Fig. 1, and also of the labeling of trays containing cards of platted lands.

The page shown in Fig. 5 has blanks J for entering the section, with its town and range to which the entries below relate, and the page shown in Fig. 6 has a like blank J' for entering the lot or the block and lot and plat to which the entries below relate. In this manner the abstracts need no rewriting to revise them, so as to get the transactions arranged chronologically, and the order or record is preserved in the libers and pages on the book, as aforesaid, to facilitate continuing abstracts to or from any date desired.

To more easily distinguish cards containing abstracts of incumbrances from conveyances, (into which two general classes I divide all instruments,) I prefer to provide cards of different colors (not shown) for the respective classes of instruments to correspond with the pages of the book just referred to. I thus have as appliances for abstracting titles a tray assigned to each section or part of a section or to a block or to a part of a block or to one or more blocks, a suitable number of cards suitably prepared as aforesaid also so assigned and one or more pages of a book also assigned in like manner, each related tray, card, and page of the book having corresponding entries indicating the particular section or block to which the instruments abstracted relate.

My method of using this device is as follows: If the instrument to be abstracted is a deed, it is noted with all the particulars, preferably on a white card. If it is an incumbrance, it is noted on a tinted card. A separate tray for the cards is provided for, and a separate account is preferably kept with each section where it is not platted and with each block of each plat or with each ten or twenty lots of every plat without blocks, as the case may be; but variations from this general rule should be made to suit individual requirements. The accounts are opened by filling out the heading J or J' of a page for deeds, preferably on

white paper, of the book hereinbefore referred to to contain such land as is most natural to gather into one account, and a like heading is made on the next succeeding page (preferably tinted) for incumbrances and the appropriate entries made in the blanks G on the corresponding tray. A book having detached leaves is preferable, as the accounts can be continued by supplying additional leaves, as required. If an instrument affects land incorporated in more than one account, copies of the abstract-cards are made and filed in as many accounts as are necessary to include the land affected thereby. After the instrument is properly noted, as aforesaid, on an appropriate card all of the tabs on the top of the card are removed, except such as indicate the land referred to in the instrument abstracted thereon. If less than a full sixteenth of a section or less than a lot is affected by the instrument abstracted, a suitable symbol is placed near the top, as at C', Fig. 2, to indicate such fact and the more particular description is entered on the lower part of the card. By this means no descriptions have to be written except those that cannot be indicated by the tabs remaining on the cards. The blanks L or M on the cards are then filled out and the date of the instrument abstracted, and also its liber and page are then entered under their proper heading in the book above referred to. The card is then deposited in its proper tray, labeled the same as the heading on the book. The deed-cards and mortgage-cards are kept separate in the tray. In this manner each instrument is noted on cards and the cards indexed and filed and all necessity for transcribing any part of the same is avoided. The tabs remaining on the cards after being deposited in the tray provide a speedy means of tracing the title to any description of the land desired, since every tab in any row from front to rear indicates that the card on which it is bears an abstract of a document affecting the portion of land represented by the tab.

Having thus fully described my invention, what I claim, and desire to secure by Letters Patent, is—

1. In a card-index for abstracting land titles, a card having tabs or projections severally representing the minor subdivisions of a quantity of land, and arranged in groups, each group representing one of the main subdivisions of the land. 115
2. In a card-index for abstracting land titles, a card having recesses in its edge dividing the same into several parts equal in number to the main divisions of the land to which the abstracts relate, and detachable tabs on each of said parts equal in number to the number of minor divisions of land in each main division represented by said part. 120
3. In a card-index for abstracting land titles, a card having recesses in its edge dividing the same into four parts indicating the respective 130

quarters of a section of land, and also having four tabs on each part indicating the respective four quarters of the respective quarter-section, and suitable letters on the tabs and 5 opposite the said parts.

4. In a card-index for abstracting land titles, a card having recesses in its edge dividing the same into four equal parts, four tabs on each of said parts, letters on the tabs representing the respective sixteenths of a section constituting a quarter-section, letters opposite said

parts and representing the respective quarters of a section of land, and blanks for entering various data on the face of the card respecting the instrument abstracted thereon. 15

In testimony whereof I affix my signature in presence of two witnesses.

FRED W. RIBLET.
